UNITED STATES PATENT OFFICE

2,593,271

ARTICLE OF FURNITURE

Blanche Lucille Cockrell, Seat Pleasant, Md.

Application August 21, 1946, Serial No. 691,955

1 Claim. (Cl. 155—43)

1

This invention relates to articles of furniture and particularly to a self-contained composite device which may be conveniently converted into several different articles of furniture. More particularly, it is directed to an improvement of the article of furniture disclosed in my copending application, Serial Number 669,634, filed May 14, 1946, which matured into Patent No. 2,512,416 on June 20, 1950.

Heretofore, convertible articles of furniture have been provided as exemplified in United States Patent Number 739,364. Such devices, however, have relatively complicated connecting components, and they are also relatively limited as to the number of different articles of furniture which they provide.

Therefore, it is an object of this invention to provide a relatively simple composite article of furniture in which its separate movable components are secured together in assembled relation by relatively simple devices.

Another object of this invention is to provide a composite article of furniture which may be conveniently and expeditiously converted into a relatively large number of different furniture pieces or assemblies.

A specific object of this invention is to provide a composite article of furniture including members for securing and supporting a composite component in position to serve as a table top or settee back, and a part of a bed or lounge, and also the provision of separate sections which unite to serve as a seat for the settee, each seat section having components which also serve as a part of a bed or lounge.

A more specific object of this invention is to provide a composite article of furniture including a support which, in collaboration with other members, supports a component of the article of furniture in position to serve as a table top or settee back or a part of a bed or lounge, means for detachably securing the component to the support, a composite seat having separate sections which form a unitary seat for the settee or form a part of the bed or lounge, the seat sections being separable to form separate benches or chairs for use when the article of furniture is arranged as a table and chair set, and means for maintaining the seat components in predetermined relation to the support.

It is also an object of this invention to provide a convertible article of furniture of generally improved construction, whereby the device will be simple, durable, and inexpensive in construction,

2

as well as conventional, practical, serviceable and efficient in its use.

With the foregoing and other objects in view, which will appear as the description proceeds, the invention resides in the combination and arrangement of parts and in the details of construction hereinafter described and claimed, it being understood that various changes in form, proportion and minor details of construction may be made within the scope of the claim without departing from the spirit or sacrificing any advantages of the invention.

For a complete disclosure of the invention, a detailed description thereof will now be given in connection with the accompanying drawings forming a part of the specification, wherein:

Figure 1 depicts, in full lines, an end view of the article of furniture with its components arranged as a table, and also shows, in dotted and dash lines, the components arranged as a settee or seat;

Figure 2 is also an end view of the article of furniture depicting the components of the seat as being separated to provide separate seats for use with the table;

Figure 3 is an enlarged vertical fragmental sectional view taken on the line 3—3 of Figure 1;

Figure 4 is an enlarged horizontal fragmental sectional view taken on the line 4—4 of Figure 1;

Figure 5 depicts, in full lines, an end view of the article of furniture with its components arranged as a bed, and also shows, in dot and dash lines, the components arranged as a lounge or sun rest;

Figure 6 is an enlarged fragmental vertical sectional view taken through the intermediate portion of the device;

Figure 7 is an enlarged fragmental front view of the device looking in the direction of the arrow 7 of Figure 6, with portions of the device being omitted for sake of clarity;

Figure 8 is an enlarged horizontal fragmental sectional view taken on the line 8—8 of Figure 7;

Figure 9 is a fragmental perspective view depicting one of the seat sections;

Figure 10 is an enlarged fragmental horizontal sectional view taken on the line 10—10 of Figure 5, parts being broken away;

Figure 11 is an end view of a modified form of the invention depicting, in full lines, the article of furniture with its components arranged as a bed, and, in dot and dash lines, as a table, settee or lounge;

Figure 12 is an enlarged vertical fragmental

sectional view taken on the line 12—12 of Figure 11;

Figure 13 is an enlarged fragmental vertical sectional view taken on the line 13—13 of Figure 11; and

Figure 14 is an enlarged fragmental vertical sectional view taken on the line 14—14 of Figure 11.

Referring to the drawings, in which similar reference characters designate corresponding parts, there is depicted, in Figures 1 to 10, a convertible article of furniture which includes a support having spaced side members or uprights 15 which are united by a transversely-extending reach or cross-brace 16 that is rigidly secured to the side members in any preferred manner. The side members may be of any preferred construction, but, in the form of the invention depicted, each side member is formed of fabricated metal of rectangular cross-section and includes spaced legs 17 which are united by vertically-spaced upper and lower cross-braces 18. Each side member 15 has its intermediate portion reduced to define opposed laterally-spaced shoulders 20, from which inclined supports 21 extend upwardly and outwardly, and these supports are united by a rail or rest 22. Each reach or cross-brace 16 is preferably of composite construction formed of opposed channel members 19 which are welded or otherwise secured in abutting relation to the upper and lower cross-braces 18.

A composite furniture component 23 is provided, and it is arranged to form either a table top or a part of a bed or settee or a part of a lounge, as will be more fully explained hereinafter. The furniture component 23 comprises a frame having straight and hollow rectangular end members 25 which are united at their terminals by angle members 26 which form the sides of the frame. The rectangular end members 25 and angle members 26 have a flat plate 27 welded or otherwise suitably secured thereto, as best seen in Figures 1, 2, 3 and 10, and this plate is arranged to provide the top of a table when the components of the article of furniture are arranged to form a table or table and chair set, as depicted in Figures 1 and 2. A cushion 28 of conventional construction is carried by a cushion frame 30 (Figures 3 and 12), and the cushion frame 30 is arranged to be snugly received in the space (Figure 10) defined by the inner walls 31 of the rectangular end members 25 and the outer or marginal flanges 32 of the angle members 26. The cushion 28 may be detachably secured to the frame 23 by any suitable means, and, as depicted in Figure 3, spring-pressed detent plungers 33, operably supported in detent housings 34 in one of the members 25, are received in shallow recesses 35 formed in the frame 30 of the cushion 28, so that the cushion may be readily removed from the frame 23 if desired. When the frame 23 is employed as a table top, the cushion 28 has no particular function and it may be removed. However, the cushion may be formed of weather-resisting material, in which event it may remain permanently fixed to the frame 23 if desired, even though the article is left outdoors.

In order to secure the furniture component 23, when employed as a table top, to the side members 15, there are provided adjustable links or legs 36. Each adjustable link includes an outer member 37 preferably formed of channel material and having an inner member or slide 38 which is longitudinally slidable therein, as best seen in

Figures 1, 2, 3 and 5. The outer terminal of each slide 38 has a thumb screw 40 swivelly secured thereto, as indicated at 41, and a similar thumb screw 42 is supported by the outer member 37, adjacent its outer terminal, for both rotary and longitudinal movement, by providing the screw with a collar 43 which is rotatably and slidably received within a cylindrical sleeve 45, welded or otherwise secured to the outer member 37, as best seen in Figure 3. The inner terminal of each outer link member 37 is reenforced by welding or otherwise securing a filler piece 46 therein (Figures 4 and 5), and the shank 47 of a third thumb screw 48 extends through aligned apertures formed in the outer link member 37 and the filler piece 46, so that the threaded terminal of the screw 48 may be threadably received in a threaded recess 50 formed in the top cross-member 18 of the side members 15, for a purpose to be hereinafter explained. The thumb screw 48 is also swivelled to the outer link member 37 by operably positioning a collar 51 carried by the screw within a cylindrical sleeve 52, carried by the outer link member 37, as best seen in Figure 4.

Each inner link member or slide 38 is provided with spaced threaded apertures 53, 54, 55, 56 in order that the inner link member 38 may be secured in different adjusted positions relative to the outer link member 37, for a purpose to be hereinafter set forth.

The outer wall 25' of each hollow rectangular end member 25 of the furniture component 23 is provided at its intermediate portion with a threaded cylindrical recess 57 (Figure 3), and each terminal of this wall 25' is provided with a transversely-disposed rectangular recess or channel 58 and an adjacent obliquely-disposed recess or channel 60. The recesses or channel 58 and 60 communicate with threaded cylindrical recesses 61 and 62 formed in the wall 25' of each rectangular end member 25 of the furniture component 23, and these pins are adapted to be received in cylindrical recesses 66 (Figure 3) formed in the upper wall of each rail 22 of each side member 15 to secure the furniture component 23 in predetermined relation to the side members 15. Similar dowel pins 67 extend perpendicularly and outwardly from each side of the furniture component 23, and these dowels are adapted to be received in cylindrical recesses 68 (Figure 6) formed in the shoulders 20 of the side members 15, for a purpose to be hereinafter disclosed.

A composite seat is provided, and it includes separate seat sections 69, and each seat section comprises a rectangular seat frame 70 (Figures 6, 7 and 9) formed of an inner side member or rail 71 and an outer side member or rail 72 and end members 73. The members 70, 71 and 72 are preferably formed of angle iron or suitable material. The seat frame 70 is supported by inner and outer legs 75 and 76, the legs being preferably formed of hollow rectangular material which is welded or otherwise secured to the components of the seat frame 70 adjacent each corner thereof. The inner portion of each seat frame 70 overhangs the inner legs 75 in order to clear the reach 16 when the seat sections 69 are at their inner or nested position to form a unitary

seat, as best seen in Figure 6. The outer portion of each seat frame 70 also overhangs the outer legs 76 to support a seat component, as will be hereinafter more fully explained. The inner and outer legs 75 and 76 are tied together by end braces 77, and the inner legs 75 are secured together by cross-braces 78, while the outer legs 76 are secured together by cross-braces 80.

Each seat section is provided with a movable or hinged frame 81 comprising parallel cross-members 82 and 83 and end members 85. These members are preferably formed of channel iron or other suitable material to thereby provide a rigid frame construction. Hinge members or ears 86 extend outwardly from the end members 85 of each frame 81, and each ear is pivotally secured to the overhanging portion of the end member of the seat frame 70, as indicated at 87, thereby permitting the frame 81 to move relative to the seat frame 70, for a reason which will be hereinafter explained. The outer terminal of each end member 85 of each movable frame 81 is provided with a transversely extending recess or channel 88 which communicates with a threaded aperture 90. Similar threaded apertures 91 or 92 are formed adjacent the channel 88 at each side thereof, and another threaded aperture 93 is formed in each end member 73 adjacent the upper terminal of each inner leg 75.

Each seat member 69 is provided with two links or legs 95 arranged to so cooperate with the components of the seat member to maintain these components in positions to form different articles of furniture. Each link 95 has a thumb screw 93 swivelly secured to one terminal and a similar screw 97 swivelly secured to its opposed terminal.

The seat frame 70 and the movable frame 81 have conventional cushions 82 and 83 suitably secured thereto. The usual supporting frames for the cushion are preferably supported by the inner flanges of the angular frame components, and the cushion frames are secured to the angular irons by screws 98, or other suitable securing devices, as best seen in Figure 6. These cushions may be removed from their frames by simply removing the screws 98, but a preferred arrangement is one in which the cushions are formed of weather-resistant material and remain permanently fixed to the seat components.

The seat sections 69 are preferably supported for movement relative to the support 15 by any preferred instrumentalities, but a convenient construction and arrangement for this purpose is disclosed in my copending application hereinbefore cited. This construction includes tubular members 100 which are secured to the intermediate portion of the reach 16 by extending the tubes 100 through alined apertures formed therein and extending bolts 101 through a flange 102 (Figure 6) carried by each tubular member 100 and through a floating flange 103. An attaching gear 105 is secured to each outer side rail 72 of each seat frame 70, and a rod 106 is secured to each ear 105, and is slidably or telescopically received within a tubular member 100, thereby permitting each seat section 69 to be moved relatively to the support 15. Each rod 106 is provided with a longitudinally extending groove 107 into which the shank of a stop screw 108 extends, so that when the seat sections 69 have reached their outermost position, their movement is limited by the stop screw engaging the inner terminal of the groove 107.

When the article of furniture is to be employed as a table, the dowel pins 65 of the furniture com-

ponent 23 are positioned within the cylindrical recesses 66 formed in the rails 22 of the side members 15. Then the thumb screw 40 of each composite link 36 is screwed into a threaded recess 51 formed in the furniture component 23, and the thumb screw 43 is screwed into the recesses 50 (Figure 4) formed in the top brace 18 of the side member 15, and the thumb screw 42 is manipulated to threadedly engage the threaded aperture 53 formed in the inner member or slide 38 of the composite link 36, thereby rigidly securing the furniture components 23 to the side members 15 to form a table top. In this position the seat components are nested in their inner position, as best disclosed in Figures 1 and 6.

However, if it is desired to arrange the components of the article of furniture as a settee, the thumb screw 42 of each composite link 36 is released so that the slide member 38 may move relative to the outer link member 37 to thus increase the length of the composite link 36. The furniture component 23 is moved to either side of the supports 21 and the dowel pins 67 are inserted into the cylindrical recesses 68 formed in the shouldered portion 20 of the side members 15. Now the thumb screw 42 of each link 36 is manipulated to screw its threaded shank into the threaded aperture 55 formed in the inner link member 38. In this position, the rectangular end frame members 25 of the movable furniture component 23 engages the outer surfaces of the inclined supports 21, so that the furniture component 23 is held rigidly to the side members 15 in position to serve as a settee back. In this position, the seat members 69 remain in their innermost or nested position to form a unitary seat for the settee, and the links 95 are secured in position to bind the movable seat components against the frame of each seat section 69, as best seen in Figures 1 and 6.

Each side member 15 has an offset attaching ear 110 extending outwardly therefrom (Figure 10), and each ear is provided with a cylindrical aperture 111 through which the shank of a thumb screw 112 extends. The shank of the thumb screw 112 is provided with a collar 113 which is mounted for rotary and sliding movement within a cylindrical sleeve 115 which is suitably secured to the attaching ear 110.

When it is desired to arrange the article of furniture as a bed, as depicted in Figure 5, the movable furniture component 23 is moved to the selected side of the support 15, and then the thumb screws 112 are screwed into the threaded apertures 63 formed in the terminal of the furniture component 23, thereby supporting this terminal of the furniture component. Now the upper terminals of the slides 38 of the composite links 36 are secured within the rectangular recesses 58 formed at the outer terminal of the furniture component 23 by manipulating the thumb screws 40 to screw them into the threaded recesses 61. Then the thumb screws 42 are screwed into the apertures 54 formed in the slides 38, thus forming legs to rigidly support the outer terminal of the furniture component 23 in position to serve as a bed.

If it is desired to arrange the components of the article of furniture to provide a lounge or sun rest, then the upper terminals of the slides 38 of the composite links 36 are secured in the oblique recesses or channels 69 formed at the outer terminal of the furniture component 23 by manipulating the thumb screws 40, and also screwing the thumb screws 42 into the threaded apertures 56 formed in the slides 38, to thus provide legs

which are rigidly secured to the furniture component 23 to support it in an inclined position to serve as the head of a lounge or sun rest.

The foot of the bed or lounge is formed by moving a selected movable frame 81 about its hinge connection 87 to horizontal position. In this position, one terminal of the link 95 is positioned in the rectangular channel 88 and is secured therein by manipulating the thumb screw formed at this end of the link, thus rigidly securing the link to the movable frame 81, so that the frame is supported to form a continuation or foot portion of the bed, as best seen in Figure 5.

When it is desired to employ the article of furniture as a table and chair set, the seat sections 69 are moved outwardly to their outer limit, as best seen in Figure 2. In this position, the seat sections 69 are arranged in proper arrangement to comfortably seat persons at the table. The seat sections 69 may be employed either as benches or chairs. If employed as benches, the movable seat frames 81 remain in their downward positions where they are held by the links 95, but if it is preferred to employ the seat sections as chairs or backed seats, then the movable frame components 81 are moved upwardly to the position shown in Figure 2, and there secured by screwing the thumb screws 97 formed at the terminals of the links 95 into the threaded apertures 91 formed at the outer terminal of the movable frame 81, thus rigidly supporting the movable frame 81 in position to form a chair or seat back.

From the foregoing, it is seen that the links 95 are employed to secure the components of each seat section in such relation as to form either a bench or chair, and to also support the movable frame 81 in position to form a part of the bed or lounge. The composite links 36 are employed to secure the movable furniture component 23 in position to serve either as a table top, settee back, or to support the head portion of a bed, lounge or sun rest.

A modified form of the invention is disclosed in Figures 11 to 14, and in this form, most of the components of the article of furniture are similar to those hereinbefore disclosed except the means for securing the table top and settee back and for supporting the bed or lounge head and foot. The furniture component 23a is similar in construction to the component 23 hereinbefore disclosed, except that it is provided at the opposed terminals of each end with threaded cylindrical recesses 116, and similar threaded recesses 117 formed intermediate the terminals of its ends, and also with a central threaded aperture 118. The side members 15a each have a housing or slideway 120 for slidably receiving supports for the bed, as will be hereinafter disclosed. Each housing 120 extends across each side member 15a, and it is provided with two elongated rectangular channels 121 and 122. Attaching flanges 123 extend outwardly from each terminal of the housing 120, and these flanges are welded or otherwise suitably secured to the legs 18a of the side members 15a to rigidly secure the housing 120 to the side members 15a.

In order to support the head portion of the bed, a leg frame 125 is provided at each side of the bed. Each leg frame includes a vertical leg 126 and a perpendicularly-disposed slide 127, the leg frame components being preferably formed rectangular in cross section, as best seen in Figure 13. The upper portion of each leg 126 has a finger 128 extending perpendicularly therefrom, and this finger is provided with a

cylindrical aperture 129 for the reception of the shank of a thumb screw 130 which is attached to the finger 128 for both rotary and sliding movement by the provision of a collar 131 carried by the shank of the screw 130 and the collar is operably supported in a cylindrical sleeve 132, which is welded or otherwise secured to the finger 128, as best seen in Figure 12. The upper portion of each leg 126 has an arm 133 pivotally secured thereto, as indicated at 135. This arm is relatively short as compared with the vertical leg 126, and it also has a finger 136 extending perpendicularly therefrom. This finger has a thumb screw 137 operably supported thereon by a construction which is similar to the device heretofore disclosed for operably supporting the screw 130. Leg frames 138, similar to the leg frames 125, are provided to support the foot of the bed, and each leg frame includes a vertical leg 140 and a perpendicularly-disposed slide 141, which is similar in construction to the leg and slide hereinbefore disclosed. The upper terminal of each leg 140 is provided with a perpendicularly-disposed finger 142 which operably supports a thumb screw 143 in the manner in which the thumb screws 130 are supported. The slides 127 and 141 are provided with stop pins 145 and 146 which are slidably received in elongated recesses or slots 147 and 148 (Figure 13) formed in the housing 120, and arranged to limit the outward movement of the slides when they have reached their outermost position, as shown in dot and dash lines in Figure 11. The rectangular end members 25a of the furniture component 23a have cylindrical threaded recesses 149 and 150 formed therein, and the angular end members 25a of the movable frame 81a are provided with threaded apertures 151.

Each cross-rail or rest 22a of each side member 15a has an angular securing finger 152 extending outwardly and upwardly therefrom, and each finger is provided with a cylindrical aperture 153 through which extends the shank of a thumb screw 155, and this thumb screw is mounted on the finger for rotary and slidable movement similar to the manner in which the thumb screw 130 is supported. Securing fingers 156 and 157, similar to the securing fingers 152, extend outwardly and laterally from the supports 21a of the side members 15a, and these fingers operably support thumb screws 158 and 160 which are operably supported in a manner similar to the thumb screws 130.

If it is desired to secure the movable furniture component 23a in position to serve as a table top, its dowel pins 65 are inserted in the receiving apertures 66, and then the thumb screws 155 are manipulated to screw them into the threaded cylindrical apertures 118 formed in the furniture component 23a, thereby rigidly securing this component to the side members 15a to serve as a table top.

When it is desired to position the movable component to serve as a settee back, it is located as hereinbefore disclosed, with its dowel pins 67 positioned in the recesses 66. Now either thumb screw 158 or 160 is manipulated so that it threadedly engages the selected threaded apertures 117, thereby rigidly securing the furniture component 23a to the supports 21a of the side members 15a.

The article of furniture may be employed as a bed by securing one terminal of the furniture component 23a to the side members 15a by means of the thumb screws 112, and raising the

selected movable frame 81a to horizontal position, as hereinbefore disclosed. Then the leg frames 125 and 138 are slid outwardly from their housing to the position indicated in dot and dash lines in Figure 11. Now the thumb screws 130 and 143 are screwed into the threaded recesses 149 and 151, thereby rigidly securing the legs 126 and 140 to the furniture component 23a and the movable frame 81a, to support these elements in position to provide the head and foot portions of a bed.

If it is desired to employ the device as a lounge or sun rest, the thumb screws 130 are released, and then the arms 133 are swung upwardly to the position indicated in Figure 11. In this position, the thumb screws 137 are screwed into the threaded apertures 150 of the furniture component 23a, thus supporting this component in an inclined position to serve as the head member of a lounge or sun rest.

The components of this device, have, for the sake of clarity, been shown in their simplest form, but it is manifest that the design may be ornamented in any desired manner without affecting its utility, and such ornamentation may readily be worked into the panels defined by the frame components of the article.

I claim:

An article of furniture including supported spaced uprights, a seat located between the uprights, a furniture component, means for locating the furniture component in horizontal position on the uprights to form a table top or in position on the uprights to form a back for the seat, composite links, each link including

5

separate members which are slidable relative to each other to thereby adjust the length of the link, means for securing the separate members of each link in predetermined relation to each other to determine the length of the link, means for securing one terminal of each composite link to the side of an upright, and means for securing the opposed terminal of the composite link to the side of the furniture component whereby the links secure the furniture component on the uprights either in position to form a table top or a seat back.
